UNITED STATES PATENT OFFICE

2,447,353

TUBULAR LAMP HOLDER

George S. Merrill, Cleveland, Ohio, assignor to
General Electric Company, a corporation of
New York

Application November 25, 1944, Serial No. 565,099

6 Claims. (Cl. 200—51.09)

1

The present invention relates to lamp holders for tubular lamps such as fluorescent lamps and especially to lamp holders for high voltage fluorescent lamps such as cold cathode lamps and instant starting hot cathode lamps.

The object of the invention is to provide an improved lamp holder for such lamps which is relatively simple in structure, safe and reliable in use, and which provides for multiple breaks of a lamp circuit when the lamp is removed from the holder so as to minimize arcing.

For a consideration of what I believe to be novel and my invention, attention is directed to the following specification and to the claims appended thereto.

In the drawing, Fig. 1 is a side elevation of a tubular lamp supported in holders embodying the invention; Fig. 2 is a longitudinal sectional view through one of the holders, a lamp end being shown in position therein; Fig. 3 is an end view with the end cover plate partially broken away; Fig. 4 is a sectional view similar to Fig. 2 illustrating the positioning of the lamp in the holders; Fig. 5 is a detail sectional view showing the positions parts of the holder occupy when a lamp end is not therein; Fig. 6 is an exploded perspective view illustrating certain parts of the holder, and Figs. 7 and 8 are views of a modification.

Referring to the drawing, Figs. 1 to 6, 1 indicates a tubular lamp mounted in holders 2 which may be alike in structure. The lamp comprises a glass tube sealed at its ends and on each end provided with a cap or lamp base 3 of insulating material fixed in position on the tube ends in any suitable manner. Each cap 3 has a projecting portion 4 provided with an axially extending bore 5 in which is located a lamp terminal 6, the terminal being spaced from the end of projecting portion 4. Terminals 6 are electrically connected to suitable cathodes located within the ends of the glass tube.

The lamp holder comprises a base 7 having walls which define a tubular housing 8 provided at one end with an opening 9 of a diameter to receive the end of the tubular lamp which is to be mounted therein. The other end of the housing is closed by a cover plate 10 fixed in position by screws 11. The base has feet 12 to receive screws 13 for fastening the holder to a support 14.

Positioned in housing 8 are two walls 15 and 16 which form contact carriers. Wall 15 is in the form of a disk and is provided with wings or projections 17 which slide in longitudinally extending grooves in the wall of housing 8. Wings

2

17 serve to fix disk 15 from circumferential movement but permit it to move axially. Disk 15 is biased against a shoulder 18 in housing 8 by a spring 19 positioned between disk 15 and cover plate 10. In disk 15 is a central opening 20 in which is located a terminal contact pin 21 which projects well beyond disk 15 as is shown clearly in Fig. 2. It is adapted to engage a lamp terminal contact 6. Arranged around opening 20 are a series of openings 22, 23, 24, 25, 26 and 27. Positioned in opening 22 is a wire terminal contact 28 to which is connected one end of a terminal wire 29, the other end being connected to a terminal bar 30 provided with a screw 31 by means of which a lead wire may be connected to it. Wire terminal contact 28 is provided with a flange 32 which fits in a recess in a face of disk 15 and is held yieldingly therein by a spring 33 located between flange 32 and the end wall of cap 34. Positioned in holes 23 to 27 inclusive are contacts 35, 36, 37, 38 and 39. Contacts 35 and 36 are connected together by a strap 40; contacts 37 and 38 are connected together by a strap 41, and contacts 39 and terminal contact 21 are connected together by a strap 42. Straps 40, 41 and 42 are located in recesses in the face of disk 15 and each is provided with outwardly extending projection as shown clearly in Fig. 5. Wire terminal contact 32 and straps 40, 41 and 42 with their attached contacts are held in position by a cover disk 43 of insulating material against which spring 19 is positioned. Wire terminal contact 28 and contacts 35 to 39 are relatively short as compared to the thickness of disk 15 so that when positioned in their respective openings, their ends are well spaced from one end of the openings. In substance, there is provided in disk 15 a number of sockets at the inner ends of which the contacts are located.

40 Wall 16 is in the form of a disk having a flange 44 between which and the adjacent surface of disk 15 there is located a spring 45 which biases disk 16 to a position wherein it engages the end wall of housing 8. Disk 16 is positioned inside of an axially extending wall 46 integral with wall 15. Wall 16 is provided with a central opening 47 through which terminal contact 21 extends. On its side adjacent to disk 15, it is provided with a series of contact pins 48, 49, 50, 51, 52 and 53 which are in line with and adapted to move in holes 22 to 27 in wall 15. When a lamp is not in position in a holder, spring 45 holds wall 16 against the end of housing 8 and when in this position the ends of contact pins 48 to 53 are positioned just within the outer ends of holes

22 to 27. This serves to keep disk 16 correctly aligned with disk 15 and to prevent its turning relative to disk 15. Also when wall 18 is against the end of housing 8, the end of terminal contact pin 21 is completely housed in opening 41, being spaced well back from the end of the opening. Contact pins 48 and 49 are connected together by a strap 54; contact pins 50 and 51 by a strap 55, and contact pins 52 and 53 by a strap 56. When a lamp end is positioned in the holder, the pins are moved down into holes 22 to 27 to engage the contacts therein as shown in Fig. 2.

In Fig. 6, the dot and dash lines indicate the alignment of the socket contacts carried by disk 15 and the contact pins carried by disk 16. Socket contact 28 is aligned with contact pin 48 and socket contacts 35, 36, 37, 38 and 39 are aligned with contact pins 49, 50, 51, 52 and 53, respectively.

In use, the two lamp holders are positioned relatively to each other as shown in Fig. 1, being spaced to receive between them the lamp with which they are to be used. When a lamp is not in the holders, the disk 16 in each holder is held against the end of disk housing 8 by spring 45. The disks 15 are held against the shoulders 18 by the springs 19. To position a lamp in the holders, a lamp end is inserted in one of the holders angularly and then pushed into the holder until the other end of the lamp will clear the other holder. This requires that the lamp end be brought substantially to the position shown in Fig. 4. When the lamp end is first pushed into the holder, disk 16 is moved axially until the contact pins engage the contacts in the bottom of the sockets after which both disks are moved together. This result is obtained because spring 19 is stronger than spring 45, it being sufficiently strong to hold disk 15 against shoulder 18 while spring 45 is being compressed. The other end of the lamp is then brought up into line with the other holder after which the lamp is permitted to move axially into the other holder. The springs 19 of the two holders serve to center the lamp in the holders. The arrangement is such preferably that a lamp terminal contact 6 engages the corresponding lamp holder contact pin 21 before the pins carried by disk 16 engage the contacts carried by disk 15. To this end, pin 21 may be connected to strap 42 by an axially yieldable connection comprising a neck which passes through an opening in strap 42 and has a head held against the strap by a spring 42a. When the lamp is in position in the holder, the circuit for the lamp is from terminal screw 31 through wire 29 to wire contact 28, thence through contact pin 48, strap 54, contact pin 49, socket contact 35, strap 40, socket contact 36, contact pin 50, strap 55, contact pin 51, socket contact 37, strap 41, socket contact 38, contact pin 52, strap 56, contact pin 53, socket contact 39 and strap 42 to the lamp terminal engaging contact 21. All the contacts are connected in the circuit in series.

A lamp is removed by first moving it axially until the one end is beyond its holder 2, then moving it down angularly out of line with the holder 2 and moving it axially out of the other holder. When the lamp is moved axially to remove it from the holders in the first instance, the pins carried by disk 16 move from engagement with the contacts carried by disk 15 thus opening the circuit at each of these points. Upon additional movement, the lamp terminal contact 6 is moved from engagement with the end of contact pin 21.

5 By this arrangement, the circuit is broken at a multiplicity of points within the disk 15. In the present instance, seven such points are illustrated. It will be understood, however, that a greater or fewer number may be used as found desirable. In any event, due to the multiplicity of points at which the circuit is broken simultaneously, the arcing at each of the points is minimized. Such arcing as occurs is confined to the sockets where 10 it is not visible and where it can do no harm.

15 While I have shown all the contact pins carried by the one disk and all the socket contacts carried by the other disk, it will be understood that this is only one arrangement and that other arrangements of the contacts between the disks may be provided, if found desirable.

In Figs. 7 and 8 is shown a construction similar to that shown in Figs. 1 to 6 except for the arrangement of the contacts on the contact carriers 57 and 58 which correspond to the contact carriers 15 and 16 of Figs. 1 to 6.

20 Contact carrier 57, which is formed of suitable insulating material, is provided with three sockets at the inner ends of which are located contacts 59, 60 and 61. Contacts 59 and 60 are connected together by a conducting strap 62 attached to carrier 15 by a screw 63. Contact 61 is connected by a strap 64 to terminal wire 65 corresponding to terminal wire 29 of Figs. 1 to 6.

25 Contact carrier 58 is provided with three contact pins 66, 67 and 68. Contact pins 66 and 67 are connected together by a metal strap 69 and contact pin 68 is connected to a terminal contact 70 by a strap 71. Terminal contact 70 is adapted to engage with the lamp terminal contact 72 at the end of lamp 73. When a lamp is positioned in the lamp holder, the circuit to the lamp is from terminal wire 65 to socket contact 61 and through contact pin 67, strap 69, contact pin 66, socket contact 59, strap 62, socket contact 60, contact pin 68, strap 71 and terminal contact 70 to the lamp terminal contact 72. In this arrangement, it will be seen that the socket contact terminal 70 is carried by the contact carrier 58, which corresponds to contact carrier 16 of Figs. 1 to 6, rather than by contact carrier 57 which corresponds to contact carrier 15 of Figs. 1 to 6. In this arrangement also spring 74, corresponding to spring 45 of Figs. 1 to 6, is arranged at the center of the contact carriers rather than at the periphery of the contact carriers. Also, in this arrangement, walls 75 and 76 which house the terminal contacts 70 and 72 telescope one within the other when the lamp end is inserted in the holder as is clearly shown in Fig. 7.

30 In the modification shown in Figs. 7 and 8, the circuit is opened initially at three points, i. e., at the three socket contacts 59, 60 and 61. The arrangement is such that when a lamp is removed from a lamp holder, the circuit is opened at contacts 59, 60 and 61 prior to separation of lamp terminal contact 72 from lamp holder terminal contact 70.

35 In connection with both structures illustrated, it will be understood that the several straps connecting the contacts will provide sufficient flexibility to insure good electrical engagement between the contacts and the contact pins.

40 In accordance with the provisions of the patent statutes, I have described the principle of operation of my invention, together with the apparatus which I now consider to represent the best embodiment thereof, but I desire to have it understood that the apparatus shown is only il-

Iustrative and that the invention may be carried out by other means.

What I claim as new and desire to secure by Letters Patent of the United States, is:

1. A lamp holder comprising a base having walls which define a cylindrical housing having a stop shoulder intermediate between its ends, a first disk in the housing, a spring biasing said disk against the stop shoulder, walls defining a plurality of spaced sockets in the disk, contacts in said sockets, a lamp terminal engaging contact carried by said disk, a second disk in said housing, a spring biasing the second disk to a position in spaced relation to said first disk, pin contacts carried by said second disk adapted to enter said sockets and engage the contacts therein when the second disk is moved relatively to the first disk by the insertion of a lamp end into the lamp holder, and means whereby when the pin contacts engage said socket contacts, the socket contacts are connected in series with said lamp terminal engaging contact.

2. A lamp holder for a tubular lamp having contact terminals at its ends comprising a base having an open end through which a lamp end may be inserted, a wall in the base remote from the open end, a lamp terminal engaging pin carried by said wall and extending toward said open end, an axially movable insulating member in the base having an axially extending opening through which said pin extends and which houses the end of the pin when a lamp end is not in position in the lamp holder, said insulating member being moved by the insertion of a lamp end into the holder to expose the end of the pin for engagement with a lamp terminal contact, a line terminal contact, a line terminal, and a plurality of pairs of contacting members carried by said wall and movable insulating member with the individual contacting members of one pair in alignment with the corresponding contact members of different pairs which when engaged with each other provide a series of contacts through which said pin is electrically connected to said line terminal.

3. A lamp holder comprising a base having walls which define a tubular housing having an open end and axially spaced stop shoulders, axially movable transverse walls in said housing, means biasing said walls against said stop shoulders, a line terminal contact carried by one of said walls, a lamp terminal engaging contact carried by the other of said walls, and a plurality of contacts and contact pins carried by said walls, said contacts and contact pins forming a plurality of circuit interrupting points in a series electrical circuit and which are brought into engagement when a lamp end is positioned in the lamp holder to connect the line terminal contact to the lamp terminal engaging contact.

4. A lamp holder comprising a base having walls which define a tubular housing having an open end and axially spaced stop shoulders, axially movable transverse walls in said housing, means biasing said walls against said stop shoulders, a line terminal contact and a lamp terminal engaging contact carried by one of said walls, and a plurality of contacts and contact pins car-

ried by said walls, said contacts and contact pins forming a plurality of circuit interrupting points in a series electrical circuit and which are brought into engagement when a lamp end is positioned in the lamp holder to connect the line terminal contact to the lamp terminal engaging contact.

5. In a lamp holder, a hollow base having two contact carrying supports therein, spring means normally tensioning one of said supports apart from the other, a plurality of contacts on each of said supports correspondingly positioned on the two supports so that the corresponding contacts will connect with each other when the supports are moved toward each other against said spring means, means connecting together non-corresponding pairs of contacts on each of the two supports so as to form a series circuit through said contacts and connecting means alternately from one support to the other, whereby the points of separation of the corresponding contacts on the two supports define a plurality of simultaneous circuit breaking points in series, a lamp terminal engaging contact connected to one end of said series circuit and mounted on one of said supports for independent axial movement and means biasing the latter contact outwardly of said base for separation from a lamp terminal subsequent to opening of said series circuit breaking points when a lamp is being removed from the holder.

6. A lamp holder comprising a base having walls which define a tubular housing having an open end and axially spaced stop shoulders, axially movable transverse walls in said housing, means biasing said walls against said stop shoulders, a line terminal contact and a lamp terminal engaging contact carried by one of said walls, and a plurality of contacts and contact pins carried by said walls, said contacts and contact pins forming a plurality of circuit interrupting points in a series electrical circuit and which are brought into engagement when a lamp end is positioned in the lamp holder to connect the line terminal contact to the lamp terminal engaging contact, and means providing independent axial movement of said lamp terminal engaging contact and biasing the latter contact outwardly for engagement with a lamp terminal prior to engagement of said contact pins with said contacts when a lamp is being positioned in the holder.

GEORGE S. MERRILL.
